APPARATUS FOR SELECTIVELY POSITION-
ING TYPEWHEELS

Reginald Dennis Salmon, Croydon, England, assignor to Creed and Company Limited, Croydon, Surrey, England, a company of Great Britain

Application May 28, 1942, Serial No. 444,860
In Great Britain July 7, 1941

12 Claims. (Cl. 178—34)

This invention relates to apparatus in which a type wheel is selectively positioned under the control of a rotatably mounted member or members having a plurality of rows of stops associated therewith co-operating with a detent or detents placed successively and selectively in accordance with a code in operative relation with the rows of stops. A teleprinter, (i. e. a start-stop printing telegraph receiver), of this kind is described in British Patent No. 473,614, whilst a power operated typewriter of this kind is described and claimed in British Patent No. 529,983.

It is the object of the present invention to reduce the speed at which the said member or members must be driven. As the shock of arresting the said member is proportional to the square of its speed this is of considerable importance in reducing wear on mechanical parts.

According to one feature of the present invention one or each of said members is provided with a plurality of different rest positions and is selectively allowed to rotate through a predetermined angle between two of said rest positions or is prevented from so rotating according to the relation between the nature of an element of said code and the rest position of said member.

The invention is applicable to a printing telegraph receiver as described in Patent No. 473,614 in which the typewheel makes one complete revolution for each half revolution of a member carrying rows of stops. As described in the said Patent 473,614 the said member has two rest positions 180° apart. The detent which is selectively moved in accordance with the nature of the first code element of the received combination arrests the said member after a rotation of 90° corresponding to a typewheel rotation of 180°. In applying the present invention to such an arrangement the member carrying the rows of stops is provided with four rest positions 90° apart and is selectively allowed a rotation through 90°.

The invention is also applicable to a printing telegraph receiver or to a power operated typewriter as described in British Patents, Nos. 534,206 and 529,983 respectively in which a typewheel is rotated under the control of one member having a plurality of rows of stops and moved longitudinally under the control of another member having a plurality of rows of stops. In applying the invention to such apparatus, either or both of the said members would be provided with two rest positions 180° apart.

According to another feature of the invention

in apparatus of the kind specified one or each of said members is provided with two different rest positions 180° apart and is selectively released for rotation through 180° or prevented from so rotating according to the relation between the nature of an element of said code and the rest position of said member.

In the arrangements of the prior art the typewheel must be returned to an unvariable starting position before it can be released by the first unit of the code. In the arrangements described in the British Patent 473,614 the speed of the typewheel must be at least 2½ times that of the cam shaft operating the detents co-operating with the rows of stops. In British Patents 534,206 and 529,983 there are described arrangements in which the speed of the typewheel is reduced by proportioning the intervals allowed for the successive movements of the typewheel so as to decrease as the degree of movement to be executed by the typewheel decreases and in this way the speed of rotation of the typewheel is reduced to twice that of the cam shaft.

The arrangement according to the present invention is independent of the improvements according to Patents 534,206 and 529,983 but may be used with the latter and if so used the speed of the typewheel is reduced to 1½ times that of the cam shaft.

30 In the preferred embodiments of the present invention the typewheel is mounted so as to rotate with a rotary shaft carrying the various rows of stops. This shaft is provided with two stops 180° apart for defining the rest positions of the shaft.

35 A first code element of a given nature, say spacing, serves to release the shaft for a rotation of 180° if it is initially in one rest position, whilst if it is initially in the opposite rest position a first code element of the opposite nature serves to release it for such rotation.

The nature of the invention will be better understood from the following description of two different embodiments thereof taken in conjunction with the accompanying drawings of which:

45 Fig. 1 is a perspective exploded view of a printing telegraph receiver according to the invention, some parts being omitted for the sake of clearness.

Fig. 2 is a like view of the printing and paper feeding mechanism of the receiver shown in Fig. 1.

Fig. 3 is a like view of additional mechanisms which may be used with that of Fig. 2 for certain applications of the receiver.

Fig. 4 is a perspective exploded view of another form of printing telegraph receiver according to the invention.

Referring first to Fig. 4 the cam shaft 1 is adapted to be clutched, upon the receipt of a starting signal, to a driving shaft, not shown, driven at a substantially constant speed. The typewheel shaft 2 is driven by means of friction clutch 3 from gear 4, which is driven from the driving motor. The typewheel shaft 2 carries normal stop arms 5 and 6, a first selecting arm (positive) 7 and a first selecting arm (negative) 8, a member 9 having second selecting arms, a member 10 having third selecting arms, a member 11 having fourth selecting arms, and a member 12 having fifth selecting arms. It should be observed that the second, third, fourth and fifth selected members have two, four, eight and sixteen arms respectively.

Co-operating with the normal stop arms 5 and 6 is a detent lever 13, normally held in engagement with the arm 5 or 6 by means of a downwardly extending portion engaging with a common latch 14 against the action of spring 15. Detents 16, 17, 18, 19, 20 and 21 co-operate with stop arms 7, 8, 9, 10, 11 and 12 respectively, each detent having a downwardly extending arm adapted to co-operate with the common latch member 14. Each detent is acted upon by a spring, tending to withdraw it from the path of its associated stop arm.

Detent 16 is provided with a third arm carrying a bearing, in which is journalled a pivot 22. The pivot 22 carries a cam lever 23 adapted to cooperate with a cam 24 and provided with a latch face 25. This latter is adapted to cooperate with one end of a cam lever 26, the other end of the lever being adapted to cooperate with a projection 27 carried by the frame 28, journalled on the pivot 38. The frame 28 is under the control of the receiving electro-magnet 29. The cam lever 26 cooperates with a cam 30, and is journalled upon a pin 31 carried by a spring-loaded lever 32.

A similar set of parts is provided in association with each of the remaining detents 17, 18, 19, 20 and 21. For example, cam lever 42 is carried by the pivot pin journalled in the third arm of detent 17, and the latch face 41 on cam lever 42 cooperates with one end of cam lever 39. Cam lever 39 is journalled upon a pin carried by a spring loaded lever 44. Cam levers 42 and 39 cooperate with cams 45 and 49 respectively.

Cam lever 39 differs however from cam lever 26 in that the former co-operates with the frame 28 and not with the frame extension 27. The cam levers associated with the other detents and corresponding to cam levers 26 and 39 co-operate with the frame 28 similarly to cam lever 39.

Cam lever 23 is provided with an extension 23a, and other similar cam levers such as 42 are provided with similar extensions, all arranged to be acted upon by a common resetting lever 33, operated by a resetting cam 34. The lever 33 is provided with a pin 35, which co-operates with a projection on the common latch 14, which is pivoted on rod 50 whereby the latch may be operated when the cam lever 23 and similar cam levers are reset. A special cam 36 is provided for operating the normal stop arm 13. A 5-hump cam 37 is provided to move the electro-magnet armature carried by the frame 28 against the poles of the electro-magnet during the receipt of the middle portion of each unit of the code.

The operation of the device is as follows: Upon receipt of a starting signal, the shaft 1 is clutched to the constantly rotating shaft driven from the driving motor by any well known means (not shown) the typewheel shaft being held by the lever 13 in the position shown, or in a position 10 180° displaced from the position shown, the detent 13 being held into engagement with one or other of the arms 5 and 6 against the action of spring 15, by means of the common latch member 14. During the receipt of the first unit of the code, the first hump on cam 37 will depress the frame 28 carrying the electro-magnet armature, so as to bring the armature into contact with the electro-magnet 29. If, at this moment, there is a current flowing in the winding of the electro-magnet, the frame 28 will be held in a downward position; if no current is flowing in the winding, the frame 28 will be released so that it will return to the position shown. Immediately after the operation of the first hump on the cam 37, when the frame 28 has taken up a selected position, the cams 30 and 49 will act at the same moment to press forward the cam 25 levers 26 and 39. With the frame 28 in the position shown, i. e. away from the magnet 29, the lower end of lever 26 is clear of the projection 27, so that it will not be held thereby. Consequently, when the cam 30 presses on the hump on the lever 26, the lower end of the lever 26 will move towards the left and the spring 40 will be slightly extended, and the upper end of the lever 26 will remain firmly in engagement with the latch 25 on cam lever 23.

Whilst the hump on cam 30 is operating cam lever 26, the hump on cam 49 is operating cam lever 39, the lower end of which is engaged by the common member 28, it being assumed that this member is in its upper position. Consequently, the lower end of lever 39 will be held and the upper end will move outwards, so as to become disengaged from the latch 41 carried by cam lever 42, so that this lever will be moved in an upward direction by spring 43, thereby preventing the upper end of cam lever 39 from returning to its normal position under the action of spring 43a. It will be observed that spring 43 urges lever 42 in a clockwise direction, thereby producing pressure simultaneously on the upper end of the lever 39 and on the hump on lever 39 that is in engagement with the cam 49. It will thus be observed that, with the latch member 28 in its upper position, as shown, cam lever 23 is held in engagement with cam 24 by latch 25 and the upper end of cam lever 26, whilst the cam lever 42 is released, so as to be moved away from cam 45, under the action of spring 43. It is clear, however, that, if the common member 28 were in its lower position against the electro-magnet 29, the lower end of lever 39 would be left free, and the lower end of lever 26 would be held by the extension 27. Consequently, lever 42 would be held and lever 23 would be left free.

Immediately after cams 30 and 49 have operated, cams 24 and 45 operate levers 23 and 42. Lever 23, which is held by latch member 25 and the upper end of lever 26, will rotate in an anti-clockwise direction round the latch member 25, thereby causing lever 16 to rotate in a clockwise direction, thus bringing one arm of lever 16 into the path of the arm 7 on the typewheel spindle and causing its downwardly extending portion to depress the common latch member 14, 75 thereby releasing the lever 13, which will be

withdrawn from the engagement with arms 5 or 6 by the spring 15. The common latch member 14 will immediately rise to hold the lever 16 in its actuated position.

The common latch member 14 is formed with a knife edge co-operating with the downwardly extending arm of each detent lever and the knife edge of the latch lies at an angle with respect to the edge of the detents in such a way that detent 16 on rotating in a clockwise direction depresses the latch to an extent sufficient to free detent 13, and similarly any succeeding detent will depress the latch to an extent sufficient to release any previously actuated detent. It should be noted that, with the typewheel held in the normal position shown, the actuation of detent 16 does not permit the typewheel to rotate except by a very small amount, which corresponds to the clearance provided between the detent 16 and the stop arm 7.

Cam 45 is ineffective on cam lever 42, because this lever has been withdrawn under the action of spring 43 from the path of the hump on cam 45. Consequently, it will be seen that, if the first impulse of the code corresponds to no current in the electro-magnet 29, the common frame 28 will be in its upper position at the moment when the cams 30 and 49 operate, and detent 17 will remain in the position shown in which it is ineffective to arrest the typewheel shaft. The typewheel shaft will always be arrested by means of arm 7 and detent 16 if the first code element be spacing. If the typewheel shaft had been resting in a position 180° from that shown by detent 13 coacting with stop arm 6, the shaft 2 would be in the circumstances detailed above move into its first selecting position through half a revolution. Similarly, if the first selecting impulse corresponds to current in the electro-magnet winding, i. e. is a marking impulse, detent 17 is actuated instead of detent 16 and the typewheel shaft makes either a half revolution or practically no movement at all, depending upon whether it was held by detent 13 being in engagement with arm 5 or arm 6.

Cam levers 46 and 47, with corresponding cams, are provided for the second unit of the code, and similar levers for the third, fourth and fifth units of the code. In each case, only one pair of levers is provided in contra-distinction to two pairs of levers provided for the first unit of the code.

The shaft 1 also carries the cams required to perform the printing and paper feed functions, the mechanism for which is not shown. This mechanism may be the same as that described hereinafter with reference to Figs. 1 to 3. After the performance of these functions the cam 34 acts on the resetting lever 33 which restores all the cam levers 23, 42 &c. into positions in which cam levers 26, 39 &c. re-engage the latch faces 25, 41, &c. At the same time the pin 35 operates the common latch 14 whilst cam 36 operates the detent 13 and all the detents 13, 16, 17, 18, 19, 20 and 21 are restored to the positions shown in the drawings. The shaft 2 is thus freed for rotation, and it rotates until detent 13 engages stop arm 5 or stop arm 6 whichever it meets first. As these stop arms are positioned 180° apart the type wheel may be stopped in either of two positions 180° apart.

The action of a cam upon lever 26 or one of the corresponding levers, followed by the action of a cam on lever 23 or one of the corresponding levers, is equivalent to two degrees of move-

ment given to a selecting member. The selective release of cam levers 26 or the corresponding cam levers therefore takes place in the middle of the corresponding signal element periods, whilst the consequent movement of the detent cooperating with the rows of stops may either take place immediately afterwards or the detents may be moved into operative relation with the different rows of stops by cams angularly displaced in a manner corresponding to the degree of movement permitted to the type-wheel by the respective rows of stops.

It is clear also that the detents 16, 17, 18, 19, 20 and 21 may be actuated under control of key board operated combination bars in the manner described in British Patent No. 529,983, the detents 16 and 17 being actuated by the same combination bar and one or the other thereof actuated according as to whether the said combination bar is moved into a given position or not.

Referring now to Figs. 1 to 3, a horizontal shaft (not shown) is continuously driven by an electric motor and this shaft is provided with gears meshing with gears 4 and 57. Gear 4 drives a type wheel shaft 2 through friction clutch 3 of any well known kind. The shaft 2 is, however, normally held stationary by one of the stop arms thereon cooperating with a corresponding detent in a similar manner to that described above. Gear 57 is fixed to a shaft 127 on which is also fixed a ratchet dog 128 of a toothed clutch of well known kind. The ratchet sleeve 129 of this clutch is slidably mounted on shaft 127 and coupled to sleeve 1 rotatably mounted about shaft 127 by two ears (not shown). Sleeve 1 carries the cams for controlling the sequence of operations of the apparatus. For the sake of clearness in the showing of certain parts the ratchet dog 128 and sleeve 129 of the toothed clutch are shown in engaged position and the sleeve 1 is shown as rotated a certain amount from its normal resting position. The ratchet dog 129 is free to move to a limited extent longitudinally of sleeve 1 and in the rest position is urged towards ratchet dog 128 by a spring 130 but is held out of engagement by means of a detent 143 in well known manner. The magnet 29 is normally energised and holds its armature 28 in attracted position.

Upon the receipt of the starting element of a signal, magnet 29 is de-energized and the armature 28 is moved away from the pole pieces by the action of a spring 141. An extension piece 138 fixed to the armature coacts with an arm 137 and moves it clear of a fixed stop 136. The arm 137 is normally held against stop 136 by a spring 135 in such a position that a shoulder on the arm 137 prevents longitudinal movement of the arm. When extension 138 on the armature 28 moves arm 137 the shoulder thereon is moved clear of the stop 136. Arm 137 is attached at one end to a bell crank 161 fixed to a rod 144 mounted for rotation in the framework of the machine (not shown). When the shoulder on arm 137 is clear of stop 136 a spring 162 rotates bell crank 161 and rod 144 in a clockwise direction and arm 137 moves longitudinally of itself. The detent 143 above referred to is fixed on rod 144 and on clockwise rotation of this rod is withdrawn from engagement with ratchet sleeve 129, which is thereupon urged by spring 130 into engagement with ratchet dog 128. Sleeve 1 is thus rotated with shaft 127.

In the embodiment shown, the type wheel re- mains at the end of a cycle of selection and

printing in the position selected, but is restored to normal position during the period of the start element of the next cycle.

At the beginning of a cycle of operations, a cam 31 is acting on a cam lever 59 to hold an extension 58 thereof in engagement with a lever 51. Lever 51 is pivoted on the pivot 164 on which detent 13 is pivoted. Detent 13 is connected thereto by spring 165. In consequence spring 165 is tensioned and detent 13 is moved into the path of stop arms 5 and 6. The latch 14 is part of a frame pivoted on a rod (not shown) and one side of the frame is extended to form a bell crank lever 52. Immediately after sleeve 1 commences to move a cam 34 on sleeve 1 acts on bell crank lever 52 to remove the latch 14 from engagement with any of the detents 16, 17, 18, 19, 20 or 21 that may be held by latch 14 in engagement with a stop arm on the type wheel shaft 2. The shaft 2 thereupon commences to rotate. Cam 34 then releases latch 14 which moves back to hold detent 13 in position. Shaft 2 comes to rest with detent 13 engaging either stop arm 5 as shown or stop arm 6.

A cam 37 on the sleeve 1 acts on an extension of the armature 28 and towards the close of the start element commences to move the armature 28 towards the poles of the magnet 29. A little before the middle of the first code element of the signal a hollow in cam 37 allows the armature 28 to be moved away from the poles of a magnet 29 by its spring 141. If however magnet 29 is now energised it holds armature 28 in attracted position. This movement of armature 28 takes place for each code element of the signal, the armature being held attracted by the magnet or allowed to move away therefrom according as the signal element is marking or spacing.

The translating mechanism in the embodiment being described is provided with a plurality of sword members one for each code element constructed and mounted as described in British Patent 245,149. Two members 61a, 61b only are shown. These members are carried by cam levers 62a, 62b reciprocated by cams 63a, 63b.

An extension 66 of the armature 28 is connected to the latter by a spring 140 and is thus moved with it. Extension 66 carries a frame 65 having two depending arms 64. As soon as the position of the armature has been determined a cam 158 on sleeve 1 moves its cam lever 159 to bring the sword member carried by the cam lever into engagement with frame 65. This frame 65 is formed with a knife edge and a knife edge 160 on lever 159 engages on one side or other of the knife edge on frame 65 to hold extension 66 and frame 65 in the position they have taken up. Each of the cams 63a, 63b is in two parts. The lower moves its corresponding sword 61a, 61b into engagement with the depending arms 64. If the armature is at this moment held attracted, the left hand projection of the sword member engages the corresponding arm 64 and the sword member is rotated in a counterclockwise direction. If the armature at this movement is away from the pole pieces, the right hand projection sword member engages the corresponding arm 64 and the sword member is rotated in a clockwise direction.

After a sword member has been thus positioned it is moved by the upper cam 63a, 63b &c. away from contact with the arms 64 whereupon cam 158 allows lever 159 to be moved by its spring away from frame 65, thus leaving this frame and

extension 66 to be positioned in accordance with the next code element. After an interval the lower cam moves the sword member towards a corresponding detent. The sword member 61a for the first element of the code cooperates with two detents 16 and 17 cooperating with stop arms 7 and 8 on the type wheel shaft. If the sword member 61a is set in marking position it actuates detent 16, if in spacing position it actuates detent 17. Whichever of the detents 16, 17 is actuated upon by sword 61a moves latch 14 in a clockwise direction and so releases detent 13. The latch 14 is restored to hold detent 16 or 17 whichever has been actuated in new position and all other detents out of the path of the corresponding stop arms. As detent 13 is released the type wheel shaft commences to rotate and according to the relation between the position of the type wheel shaft and the nature of the first code element it is allowed to move only a very small fraction of a rotation or through 180°.

Thus, suppose the type wheel to have been arrested in the position shown by the engagement of detent 13 with stop arm 5. If now sword 61a has been set by a marking element and has engaged detent 16, the type wheel shaft is almost immediately arrested by engagement of detent 16 with stop arm 7. It is necessary to allow a small clearance between the positions of stop arms 5 and 7 to make certain that detent 16 will be moved into the path of stop arm 7 and will not foul the end of the stop arm. If, however, sword 61a is set by a spacing element and engages detent 17 the type wheel shaft is allowed to rotate through 180° until detent 17 engages stop arm 8.

Suppose on the other hand the initial position of the typewheel shaft to have been 180° from that shown, i. e. detent 13 in engagement will stop arm 6. Then if detent 16 were actuated for a marking element, the type wheel shaft would rotate through 180° until detent 16 engaged stop arm 16. If detent 17 were actuated by a spacing element, the type wheel would only rotate a very small amount and would be arrested by engagement of detent 17 with stop arm 8.

The sword member 61b for the second code element is moved similarly to sword member 61a. The sword member 61b however cooperates with only a single detent 18 which it engages only if it has been set by a spacing element of the code. If the second element of the code be marking sword member 61b is set in a position in which it does not engage detent 18 and the type wheel shaft is not in that case released.

The sword members (not shown) for the third, fourth and fifth code elements co-operate with detents 19, 20 and 21 in the same manner that sword member 61b co-operates with detent 18. Detent 18 cooperates with two stop arms 9, detent 19 with four stop arms 10, detent 20 with eight stop arms 11 and detent 21 with sixteen stop arms 12.

The reason for the resilient connection between detent 13 and lever 51 will now be apparent. If the second, third, fourth and fifth elements of a code combination are all marking the shaft 2 will remain, at the end of the receipt of such combination, in a position in which it is held by either detent 16 or detent 17 co-operating with its corresponding stop arm 7 or 8. Stop arm 5 or stop arm 6 will then be in the path of detent 13 and it cannot therefore be pushed into operative position. When the

latch 14 is moved to release detent 16 or detent 17, the shaft 2 moves and detent 13 will snap into position just behind the stop arm against which it has been moved by the spring 165 and into the path of the stop arm 180° away from it.

The latch 14 is disposed with reference to the detents 13, 16, 17, 18, 19, 20 and 21 in a manner similar to that in the embodiments previously described. Detent 13 can accordingly be moved past latch 14 at the commencement of a cycle of operations without moving the latch far enough to release any other detent that is in position, but any detent subsequently actuated will release any previously actuated detent.

The periods between the times at which the sword members act upon their corresponding detents preferably decrease as the degree of movement to be executed by the shaft 2 decreases and accordingly each sword member is restored to an intermediate position after being set by the armature extension in which it may remain before being moved to act upon its corresponding detent.

During the rotation of cam sleeve 1 cam 133 acting on cam lever 131 gradually rotates rod 144 to bring detent 143 into position to re-engage a cam surface on ratchet sleeve 129 in order that it may withdraw this ratchet sleeve from engagement with ratchet dog 128 against the action of spring 136. As rod 144 rotates, bell crank lever 161 rotates with it and withdraws arm 137 from engagement with extension piece 138 until the shoulder on arm 137 is in position to engage fixed stop 136. Near the end of a cycle rotation the cam 133 leaves lever 131, rod 144 and detent 143 free, since they are now held by engagement of the shoulder on arm 137 with the fixed stop 136. The cam sleeve 1 comes to rest during the period of the stop element the ratchet sleeve 129 having been withdrawn from engagement with ratchet dog 128.

It will be seen from Fig. 1 that the characters on the type wheel are arranged in two rows, letters in one and figures and punctuation marks in the other. The particular row of characters to be presented to the paper tape is determined by shift signals viz: the "Letter shift" or the "Figure shift" signals. The reception of either shift signal sets the type wheel shaft 2 in a characteristic position as in the case of any other signal. The type wheel 147 is fixed to a sleeve 60 splined to shaft 2 so as to rotate therewith but free to move longitudinally thereof. Sleeve 60 carries a plate 152. Once per revolution of cam sleeve 1 after the rotation of the type wheel has finished, cam 157 thereon strikes a lever 151 pivoted at 154, downwardly and cam 156 strikes a lever 153, pivoted at 155 upwards. If "Letter shift" has been selected plate 152 is positioned below lever 151 and if "Figure shift" is selected, plate 152 is positioned above lever 153. In consequence the sleeve 60 with the type wheel will be raised or lowered. The type wheel will be held in one or other of these positions by means of a jockey roller 80, Fig. 2 engaging in one or other of two depressions 79 on the sleeve 60.

Printing and paper feeding operations are carried out in the following manner. Whilst the type wheel is being rotated in accordance with the incoming code elements, cams 132 Fig. 2 rock a frame 134, pivoted on rod 166, in a clockwise direction. A trunnion 88 on arm 91b of the frame 134 rotates bell crank 85 anti-clockwise on pivot 97. Bell crank 87 pivoted at 86 on the long arm of bell crank 85 is thus moved

with bell crank 85. Bell crank 87 is formed with an upstanding portion 87a. This upstanding portion moves against a downwardly extending extension 90a of a lever 90, which lever is normally resting with an upstanding extension 94 thereof against fixed stop 93, and rotates this lever anti-clockwise, extending spring 84. Lever 73 fixed on pivot rod 97 is constrained by spring 92 to follow lever 90. As trunnion 88 reaches the end of its travel an arm of bell crank lever 87 meets a latch 89 and is thus rotated slightly clockwise. The upstanding portion 87a is moved clear of the downward extension 90a and lever 90 is thus allowed to rotate in a clockwise direction under the action of spring 84. An extension 74 on lever 90 rotates lever 73. As the printing hammer 150 is fixed on rod 97 it is moved with lever 73 first away from the type wheel and then towards it. The clockwise movement of lever 90 is arrested by the stop 93, but the momentum of lever 73 and the printing hammer 150 carry them on until the printing hammer strikes the ink ribbon and paper tape against the type wheel. The spring 92 draws them again away from the type wheel.

The character selected is printed on two paper tapes. One tape only 167 is shown in Fig. 2 passing between two folds of an ink ribbon 168. The character is thus printed on the face of the tape 167 and also in reverse on the back of the tape. A second tape, not shown, passes between the rear fold of the ink ribbon 168 and the type wheel so that a character is printed on the face of the tape. Both tapes pass over a feed roller 35 68 fixed on spindle 67.

When the lever 73 is moved to bring printing hammer 150 against the type wheel, it strikes a lever 72 pivoted on a fixed pivot (not shown) and so removes it from engagement with a bell crank 95. Bell crank 95 is rotated by spring 96 and pawl 70 rotates ratchet wheel 69 by the space of one tooth. Ratchet wheel 69 is fixed on spindle 67 and thus the paper is fed by the space of one character.

When lever 85 is rotated clockwise during the first part of the next cycle a short extension 75 of this lever engages a pin 71 fixed to bell crank 95 and relatches it against lever 72 thereby withdrawing pawl 70 by the space of one tooth.

The ink ribbon 168 is fed from a mechanism (not shown) described in United States Patent No. 2,090,811, the feeding pawl being actuated by means of a bell crank (not shown) moved by arm 91 of frame 134.

When a shift signal is received, the jockey roller 80 is forced out of engagement with the sleeve 60 and lever 78 is rotated in an anti-clockwise direction against spring 77. Lever 78 engages a pin 82a on latch 82 and moves this latch clockwise out of engagement with latch 89. Latch 89 moves anti-clockwise about its pivot 76, so that as bell crank 87 moves anti-clockwise with lever 85, it will not be arrested by latch 89 and will not release lever 90. The rapid movement of this lever under the action of spring 84 is, therefore, prevented, and no printing or tape feed ensues.

If the typewheel be moved, in response to the space signal, to a position in which there is a blank on the typewheel, a pin 149 (Fig. 1) on the latter actuates lever 146 and moves the free end of the lever into the path of a projection on the type hammer, so that the latter will be arrested before it reaches printing position, but not before lever 72 is struck by lever 73. The

tape will therefore be fed in the normal manner but no printing will take place.

The machine may be used as the printer portion of a cyphering machine and if it be so used for printing a cyphered message, it is necessary to insert a space after every five characters. When frame 134 is moved in an anti-clockwise direction, arm 91a moves a pawl 115, Fig. 3 into engagement with a ratchet wheel 114 fixed on the same shaft 67 as the normal ratchet feed wheel 69. Ratchet wheel 114 is provided with one sixth of the number of teeth on ratchet wheel 69, in the present case four teeth to 24 teeth in wheel 69. Thus, after every five steps that ratchet wheel 69 has been moved ratchet wheel 114 is moved by pawl 115 to rotate the shaft 67 and ratchet wheel 69 by an additional tooth. The rotation of the shaft 67 by the action of pawl 115 on ratchet wheel 114 takes place in the cycle following that in which a notch in the wheel 114 is presented to the pawl and in this last mentioned cycle before printing takes place.

If the machine is set for any other condition than typing a cypher message a control lever disables the mechanism for inserting a space after every five characters. This control lever rotates a spindle 112 clockwise and by means of levers 111 and 113 holds the pawl 115 from engagement with ratchet 114.

In order that paper tape may be conserved, a device has been provided, whereby when the machine forms part of a transmitter and receiver and a local record of transmitted messages is not required, the paper feeding mechanism may be put out of action. This device is associated with the send-receive switch so that the device can only be operated when the switch is in "send" position. Cam 125 Fig. 3 is mounted on a spindle, terminated with a knurled knob 126 projecting through the top plate (not shown) of the machine. This knob has two positions marked "Non-feed" and "Feed." When turned to the "Non-feed" position, the cam 125 acts on a rod 124 supported on a lever 123 pivoted about rod 166. A lever 120 is fixed on a rod 122 mounted on lever 123. Lever 120 is normally held by spring 121 in engagement with bell crank lever 82 and when cam 125 acts on rod 124, lever 120 rotates bell crank 82 clockwise against the action of spring 81 and so removes the shoulder thereon from engagement with latch 89. This latch thus rotates anti-clockwise, when permitted to do so by pin 98 on arm 91b of frame 134, and moves out of the path of bell crank 87. The printing hammer is then not tripped nor the tape fed during subsequent action of the machine. In order to ensure that the above arrangement is inoperative when the machine is receiving from a distant station, the spindle 119 is coupled to the operating rod of the send-receive switch. When this switch is moved into receive position, the rod 119 is turned clockwise carrying with it lever 117 against the action of spring 116. Rod 118, fixed on lever 117, is therefore moved against lever 120 moving it clear of bell crank 82, which thereupon returns to normal position.

What is claimed is:

1. A printing telegraph receiver comprising a rotatable type wheel, and mechanism responsive to a received signal sequence for rotating the type wheel into selected printing position comprising a rotary selector unit associated with the type wheel, an intersignal stop device arranged to stop the selector in either of two positions between signal sequences, and a series of selective stop

devices successively responsive to signal sequence elements arranged to arrest the selector unit in selected position, including a first selector stop device responsive to the first selector signal element arranged to stop the selector unit initially in either one of two positions in axial register with said intersignal stop positions.

2. A printing telegraph receiver as set forth in claim 1, in which said stop positions are circumferentially spaced by 180°.

3. A printing telegraph receiver as set forth in claim 1, in which said first selector stop device includes two separate rotary stops carried by the selector unit, and separate detents each engaging one of said rotary stops.

4. A printing telegraph receiver as set forth in claim 1, in which each stop position of the intersignal stop device is slightly spaced in advance of the corresponding stop position of said first selector stop device by a distance sufficient to permit positive interference-free engagement upon operation of the latter device when the intersignal stop device is released.

5. A printing telegraph receiver comprising a rotatable type wheel and mechanism responsive to a received signal sequence for rotating the type wheel into selected printing position comprising a rotary selector unit associated with the type wheel including a series of stops, a series of detents each associated with a stop, and means responsive to the signal sequence elements for selectively shifting said detents into stop engaging position, at least one of said detents being provided with a yieldable joint arranged to prevent damage to a detent obstructed by a stop during said shift.

6. In a printing telegraph receiver of the type including a rotatable type wheel and mechanism responsive to a received signal sequence for rotating the type wheel into selected printing position, a rotary selector unit associated with the type wheel and including a series of unit stops, each stop including a plurality of circumferentially spaced stop members, the members of successive stops being spaced by progressively decreasing angles, a series of detents each associated with a given stop, and means responsive to the signal sequence elements for selectively shifting said detents into stop engaging position, a detent actuating member associated with each given detent, means responsive to a signal element for selectively setting each actuating member in and out of operative position, and means for thereafter operating said actuating member, said last-mentioned means for operating the actuating members operating successive members at decreasing time intervals corresponding to said decreasing angles.

7. A printing telegraph receiver as set forth in claim 6, including cam means for shifting the detents into stop engaging position.

8. A printing telegraph receiver as set forth in claim 6, including cam means for operating the actuating members.

9. A printing telegraph receiver comprising a rotatable type wheel, mechanism responsive to a received signal sequence for rotating the type wheel into selected printing position and means for longitudinally shifting the type wheel including a longitudinally movable and rotatable type wheel support, longitudinally movable actuating means adjacent the support, means for moving said actuating means upon the reception of each signal sequence, and means responsive to a signal sequence for shifting said type wheel support

selectively into and out of position for engagement by said actuating member.

10. A printing telegraph receiver for printing five unit code messages comprising printing mechanism, means responsive to successive received signal sequences for selectively actuating the printing mechanism to print a character for each sequence, means for feeding a tape past the printing mechanism by steps corresponding to the receipt of signal sequences, and means for automatically feeding the tape an extra step after the printing of five characters thereon.

11. A printing telegraph receiver as set forth in claim 10, in which the tape feeding means comprises a ratchet, an associated pawl, means for actuating the pawl once for each signal se-

quence received to advance the tape one step, a second ratchet, an associated pawl, and means actuated at the end of each signal sequence for operating the second pawl to advance the tape an additional step.

12. A printing telegraph receiver as set forth in claim 10, in which the tape feeding means comprises a ratchet, an associated pawl, means for actuating the pawl once for each signal sequence received to advance the tape one step, the extra step feeding means including a second ratchet and an associated pawl, and means for disabling the second pawl and thereby eliminating automatic spacing between code units.
